DESIGN FOR A PITCHER

John H. McKinnon, Marshall, Tex.

Application December 19, 1947, Serial No. 143,240

Term of patent 14 years

(CL. D44—21)

To all whom it may concern:

Be it known that I, John H. McKinnon, a citizen of the United States, residing at Marshall, in the county of Harrison and State of Texas, have invented a new, original, and ornamental Design for Pitcher, of which the following is a specification, reference being had to the accompanying drawing, forming part thereof.

Figure 1 is a side elevational view of a pitcher, embodying my novel design.

Figure 2 is a front elevational view of the pitcher;

Figure 3 is a rear elevational view; and
Figure 4 is a top view thereof.

I claim:

The ornamental design for a pitcher, as shown.
JOHN H. MCKINNON.
